VACUUM CLEANER

Gregory Fossella, Marshfield, Mass., assignor to Proctor-Silex Incorporated, Philadelphia, Pa., a corporation of New York

Filed Sept. 9, 1968, Ser. No. 13,449

Term of patent 14 years

Int. Cl. D7—06; D15—07
U.S. Cl. D49—13

FIGURE 1 is a perspective view of a vacuum cleaner embodying my new design;

FIGURE 2 is a side elevational view thereof;

FIGURE 3 is a top plan view thereof;

FIGURE 4 is a bottom plan view thereof;

FIGURE 5 is a front elevational view thereof; and

FIGURE 6 is a rear elevational view thereof.

The dominant features of my design reside in the portion shown in solid lines.

I claim:

The ornamental design for a vacuum cleaner, as shown and described.
